UNITED STATES PATENT OFFICE.

HOWARD I. WOOD, OF SCHENECTADY, NEW YORK, ASSIGNOR TO GENERAL ELECTRIC COMPANY, A CORPORATION OF NEW YORK.

ELECTRIC VAPOR-LAMP.

No. 831,400.

Specification of Letters Patent.

Patented Sept. 18, 1906.

Application filed July 21, 1902. Serial No. 116,463.

To all whom it may concern:

Be it known that I, HOWARD I. WOOD, a citizen of the United States, residing at Schenectady, county of Schenectady, State of New York, have invented certain new and useful Improvements in Electric Vapor-Lamps, of which the following is a specification.

The invention which I have hereinafter described and claimed relates to improvements in electric lamps of the type in which electric energy is converted into light by the passage of an electric current through matter in the form of a vapor or gas.

My invention consists in certain improvements in the lamp and in the means for starting the arc, to be more particularly pointed out in the claims.

Figure 1 shows one form of my invention, and Fig. 2 shows a modified form. Figs. 3 and 4 are detail views of parts shown in Figs. 1 and 2, respectively.

In Fig. 1 a lamp embodying my invention is shown, in which 1 represents a substantially vertical vacuum-tube of somewhat indefinite length, as indicated by the dotted lines at 2. A quantity of mercury 3, forming the cathode-terminal of the lamp, is placed in the bottom of a tube in direct contact with the sealed-in terminal 4. This terminal 4, which is preferably made of platinum wire, passes through the walls of the tube and is connected to the negative main 6 by the line 5. A main switch 7 is shown, by which the line 5 may be opened or closed. The main anode of the lamp consists of a bell or bottle shaped mass 8 of iron, carbon, silicon, graphite, or other suitable material, preferably iron or graphite, which is suspended from the top of the tube by the sealed-in platinum wire 9, to which it is directly attached. A small conductor, consisting of a carbon filament or rod 10, may be hung from the anode 8, if desired, to extend throughout a considerable portion of the tube. This filament is held in a central position in the tube by means of the cross-arms 11 of carbon filament, which are secured to the main filament by means of carbon paste or in any other suitable manner. These cross-arms 11 are staggered with respect to one another, so as to sustain the central filament from all sides. While I have shown and described a carbon filament, any suitable substance, such as graphite or

graphite and carbon, may be employed for the rod or cross-arms, and of course it is not essential that the cross-arms be of the same material as the rod 10 or of the shape shown. I have found, however, that a carbon filament with carbon cross-arms secured by carbon paste to be very satisfactory. The leading-in wire 9 is connected to the positive main 13 by the line 12. 14 represents an electromagnet, part of the winding of which is furnished by coils in the line 12. The line 12 also furnishes the coils for the solenoid 15, which operates the electromagnetic switch 16. The switch 16 is located in the line 17, which connects the main 13 to the sealed-in platinum wire 18. The line 17 is also coiled several times around the core of the electromagnet 14. The platinum wire 18 passes through the wall of the tube 1 and extends into the tube a short distance, the end within the tube being bent, as clearly shown in Fig. 3, to form a horizontal journal 19, on which a bar or arm 20 is pivotally mounted. Suitable washers or enlargements 19' are provided to retain the bar 20 in proper position on the journal 19. This arm 20 is formed with an enlargement intermediate its ends, and in this enlargement 22 a hole 22' is formed, which makes the bearing for the journal 19. The arm 20 is made of some conducting substance, preferably platinum, and carries at one end the auxiliary terminal 21, which consists of a ball or bullet shaped mass of iron, carbon, silicon, graphite, or other suitable material, preferably iron or graphite. The other end of the arm 20 is provided with a counterweight 23, made out of glass or other suitable material. This counterweight is made sufficiently heavy to partially overcome the weight on the other end of the arm 20. The arm 20 is preferably of such length and so proportioned that the terminal 21 and the counterweight 23 will easily clear the wall of the tube 1 when the arm 20 is in a horizontal position. The wire 18 is located above the surface of the mercury 3 at a distance somewhat less than the length of the terminal-carrying end of the arm 20, so that in its normal condition the terminal 21 rests on the surface of the mercury, with the arm 20 somewhat inclined to the vertical, though the degree of the angle is immaterial. A mass of iron or other magnetic material 24 is placed on the rod 20 near

the terminal 21. The electromagnet 14, hereinbefore referred to, is mounted close to the wall of the tube 1 and in a plane somewhat above the surface of the mercury in a position substantially diametrically opposed to the wire 18, with its axis perpendicular to the axis of the tube, and is when energized of such strength and is so located as to attract the mass 24 and lift the arm 20 into a position substantially horizontal. Adjustable resistances 25 and 26 are located in the lines 12 and 17, respectively.

The operation of my device is as follows: On closing the main switch 7 current passes from the main 13 by way of line 17 through the resistance 26, through the closed switch 16, around the core of the electromagnet 14, through the leading-in wire 18, arm 20, mercury 3, terminal 4, and line 5 back to the main 6. This current energizes the electromagnet 14, attracts the mass of iron 24, and thus raises the arm 20 to a horizontal position. As the terminal 21 leaves the surface of the mercury an arc is started, and the mercury-vapor is put into a conducting condition by means of this arc, so that current will flow between the main terminals 3 and 8 at the normal voltage at which the lamp is operated. The circuit for the current between the main terminals is traced as follows: from main 13 through the variable resistance 25, switch-coil 15, winding of the electromagnet 14, leading-in wire 9, anode 8, through the mercury-vapor from the anode 8 to liquid mercury 3, leading-in wire 4, line 5, to the negative main 6. The presence of the filament 10 seems to enable the arc to form more readily between the main terminals of the lamp. The action apparently is one in which the conducting vapor first reaches the end of the filament and then flows along the same by virtue of its conducting or other quality until it reaches the anode. The use of this filament is particularly advantageous in long tubes. The passage of current through the winding 15 operates to open the switch 16, and thus disestablishes the circuit through the line 17. The bar 20 is retained, however, in its elevated or horizontal position by the magnet 14, which is now energized by the current passing through line 12. The passage of the current through the mercury-vapor creates the light desired, which is continued as long as the current passes.

It is desirable that the terminal 21 be raised from the surface of the mercury while the lamp is in operation, as when in contact with the mercury it is subject to local heating and causes disturbances in the arc between the main terminals, probably due to the fact that when heated it gives off gases contained within it and also is volatilized to a certain extent or at least creates some detrimental actions.

In Fig. 2 I have shown a slightly-modified form of my invention. In this form the tube 1 is placed in position substantially horizontal, a cup-shaped enlargement or recess being formed on the lower side of the tube at the end opposite the anode. This enlargement or recess contains the liquid mercury. The leading-in wire 4 is passed through the wall of the tube at the bottom of the depression. In this form the auxiliary leading-in wire 18' enters the tube from the top and is curved, as shown in Fig. 4. The arm 20' is mounted thereon as the arm 20 is mounted on the wire 18 in the other form. A terminal 21', similar to 21, is mounted on one end of the arm 20, but the mass of magnetic material 24' is placed at the opposite end of the bar from that carrying the terminal 21'. In this form a separate counterweight can in general be dispensed with, as the mass of iron 24' is so located and proportioned as to form a proper counterweight for the terminal 21'. The arm 20' is connected to the wire 18' in the same manner as the arm 20 is connected to the wire 18, this being clearly shown in Fig. 4. The electromagnet 14' is located to the right of the end of the tube, as shown in Fig. 2, and is inclined about forty degrees to the horizon, with its upper end adjacent to the glass and at an elevation about midway between the level of the mercury and the pivotal point of the arm 20'. As shown, the arm 20' turns in a vertical plane passing through the axis of the tube. The magnet 14' is also located in this plane, though of course it is to be understood that the exact location and proportioning of these parts and their construction may be varied somewhat without departing from my invention. The operation of this form will be readily understood from its description and the description of the operation of the preceding form.

Some of the troubles experienced in the construction and operation of this type of lamp arises from the difficulty in obtaining and maintaining the extremely high vacuum which is necessary to the successful operation of the lamp. The introduction within the vacuum-tube of any solid material, such as the arc-starting devices are made from, is attended with the evil that they contain gases within them or upon their surfaces which are not readily removed, but which tend to be released during the commercial operation of the lamp. Hence it is desirable that these devices be of as little mass and as compact as possible and that they be made from substances which contain but small quantities of gas within them or upon their surfaces and which do not give off gas in the generation of the lamp. My arrangement of a pivoted auxiliary terminal for use as a starting device, particularly when constructed from the materials specified, possesses those characteristics in a high degree.

It will be readily understood that in some instances I may dispense with the counter-weight 23 and that I may employ a separate electromagnet for each of the circuits 12 and 17 instead of the single electromagnet 14, which I have shown.

Other changes of form and proportion are within the scope of my invention, and I do not intend to be limited to the exact form shown.

What I claim as new, and desire to secure by Letters Patent of the United States, is—

1. The combination with the inclosing envelop of a vapor-lamp, of main terminals, an auxiliary terminal in contact with one of the main terminals when the lamp is inoperative, means for separating the last-named terminals operated by the current passing between them, and means for holding them separated, operated by the current passing between the main terminals.

2. The combination with the inclosing envelop of a vapor-lamp, of a main terminal, an auxiliary terminal in contact with the main terminal when the lamp is inoperative, means for separating the terminals to start an arc, and separate means for maintaining the separation of the terminals.

3. In a lamp of the character described, movable means for starting an arc, means for moving said starting means, and means independent of said operating means for maintaining said starting means in the position to which it has been moved.

35 4. The combination with the inclosing en-

velop of a vapor-lamp, of a conducting-rod filament or the like provided with positioning cross-arms.

5. The combination with the inclosing envelop of a vapor-lamp, of a flexible conducting rod or filament or the like provided with positioning cross-arms. 40

6. The combination with the inclosing envelop of a vapor-lamp, of a carbon filament provided with positioning carbon cross-arms. 45

7. The combination with the inclosing envelop of a vapor-lamp, of a conducting rod or filament attached to the envelop at one end and provided with positioning cross-arms intermediate its ends. 50

8. The combination with the inclosing envelop of a vapor-lamp, of a conducting rod or filament provided intermediate its ends with a plurality of positioning cross-arms staggered with respect to one another.

9. In a lamp of the character described, the combination of a vaporizable main terminal and a pivoted auxiliary terminal adjacent thereto and provided with a counter-weight.

10. The combination with the inclosing envelop of a vapor-lamp, of a conducting rod or filament, and positioning devices carried by the rod or filament.

In witness whereof I have hereunto set my hand this 18th day of July, 1902.

HOWARD I. WOOD.
